CHANDELIER

Richard Kelly, New York, N. Y.

Application May 19, 1955, Serial No. 36,114

Term of patent 14 years

(Cl. D48—23)

The single drawing figure is a front view of a chandelier showing my new design. The main portion of the chandelier is of generally spherical configuration and hence the chandelier presents essentially the same appearance, irrespective of the angle from which it is viewed.

I claim:

The ornamental design for a chandelier, substantially as shown and described.
